United States Patent Office.

FRANCIS CURTIS, OF AUBURNDALE, MASSACHUSETTS, ASSIGNS ONE-HALF OF RIGHT TO WILLIAM RUSSELL & SON, OF LAWRENCE, MASSACHUSETTS.

Letters Patent No. 62,942, dated March 19, 1867.

IMPROVED SCREEN PLATE FOR PAPER MACHINERY.

The Schedule referred to in these Letters Patent and making part of the same.

TO ALL TO WHOM THESE PRESENTS SHALL COME:

Be it known that I, FRANCIS CURTIS, of Auburndale, in the county of Middlesex, and State of Massachusetts, have invented a new and useful or Improved Screen Plate for Paper Machinery, and do hereby declare the following to be a full, clear, and exact description thereof, reference being had to the accompanying drawings, making part of this specification, and in which—

Figure 1 is a top view or plan.

Figure 2, a longitudinal section; and

Figure 3, a transverse section of a screen plate or one section thereof, constructed in accordance with my invention.

In the drawings above referred to, A denotes the body of the plate, and *aa* the shallow and narrow slots or saw-kerfs, through which the paper pulp passes and is "screwed," as it is termed, the bars or portions of the body between the slots, being shown at *dd*, &c. The body of the screen is chambered or recessed below each slot, as seen at *b* in the drawings.

The above is the usual mode of construction of screen plates. My invention, however, does not consist in the construction of the plate but in the material of which it is composed, or of making it of hard rubber in place of the metallic ones now used. The slots of the metallic plate, in the operation of cutting them, have their lower edges left in a rough state or with a "burr" upon them. The threads or fibres of the paper pulp, in passing through these slots of the screen, are often stopped and collected by this rough edge or "burr," and clog or fill up the slots, causing much inconvenience and loss of time in cleaning them. Furthermore, the bars between the slots of the metallic screen plate in time often become bent out of place or out of vertical parallelism with each other, and by this means enlarge the area of the slots so that the pulp passes through them in large quantities and without being screened, an evil well understood by practical paper makers. Again, the acids contained more or less in the pulp or in its sizing, injuriously affect the material composing the metallic plate. The hard rubber plate of my invention can be manufactured at less cost than the metallic one, and is much more durable. In constructing the plate of hard rubber these evils are overcome and other advantages gained, which will readily show themselves to men practised in the art of paper making, and to whom this specification is chiefly addressed: first, owing to the peculiar nature of the rubber there is no roughness or "burr" left upon the edges of the slots, whether they be cut by machinery as the metallic ones are now cut, or whether they be formed by pressure in a mould during process of vulcanizing; second, by the elastic properties of the rubber the bars *dd* will return to place automatically should they at any time be forced out of parallelism with each other or otherwise misplaced or bent; third, the surface of the rubber is not in the least affected by the action of acids. In addition to these facts, the hard rubber plate can be manufactured at less cost than the metallic one, and is infinitely more durable.

I claim as my invention—

A screen plate for paper machinery, constructed of the material known as hard rubber.

FRANCIS CURTIS.
